DES. 2047

Elmer S. Hey of Lowell Massachusetts
Assignor to Lowell Manufacturing Company of the same place
Letters Patent No. 2047. Dated April 11. 1865.
Design for a Carpet Pattern

The schedule referred to in these Letters Patent and making part of the same.

To all whom it may concern:

Be it known that I Elmer S. Hey of Lowell in the County of Middlesex and State of Massachusetts, have originated and designed a New Pattern for Carpets or other fabrics, of which the following is a full clear and exact description, reference being had to the accompanying drawings, making part of this specification.

A is a ground composed of little diamonds surrounded by key work and small blocks all resting on the plain ground B.

C is a broad band, its particular form of it is shown in the drawing.

I, 2, 3, in the corners when matched will form a figure similar to A, B, C, D, D, D, D are four halves of a group of shells as shown in the drawing.

4, 4, 4, 4, are chains connecting figure D, D, D, D.

The remainder of the design is composed of scroll work and sprigs.

The colors employed for the different portions of the design, may be varied to suit the taste and wish of the manufacturer.

Claim.

What I claim as my invention and desire to secure by Letters Patent, is the Design or Pattern for Carpets or other fabrics, herein set forth.
